UNITED STATES PATENT OFFICE

JOHN FRANCIS CURRIVAN, OF MILTON, MASSACHUSETTS

WINDOW-CURTAIN CONTROL

Application filed April 21, 1928. Serial No. 271,810.

The control of rear window glare by the manipulation of the usual curtain from the driver's seat has been long contemplated and various means proposed. Most of these have been elaborate arrangements and have not come into any general public use apparently as involving too much trouble in installation or too much expense.

The problem is really one of supplying a cheap and efficient means by which the average car may be made self-protecting. That is to say, the requirement is for a simple device which will have a rapid and positive action so that the curtain can be raised or lowered at will to protect the driver from the glare of following headlights or to give rear vision in backing up or at other times when it is imperative that the driver should look behind.

I have therefore dealt with this problem on a basis which provides for an inexpensive equipment readily installed and which if adopted by even an average portion of motorists will reduce the number of accidents due to the glare or the drawn curtain, both of which are well recognized factors in accidents.

The real problem as sensed by me has been to provide such simple apparatus and yet have it operable by the driver without requiring an act which would interfere with his control of the car. This seems to have been one of the difficulties with previous devices. The driver has usually been compelled to go through a series of motions which distracted his attention and took so much time that there was opportunity for the very disaster that he was trying to avoid.

My invention contemplates an operation which is practically instantaneous and does not require the attention of the operator but may be performed by a single movement of the hand without the necessity of even having the driver divert his attention from the road. The solution of this problem is illustrated in the accompanying drawing, as follows:

In Fig. 1 I have diagrammatically illustrated a characteristic hookup.

Fig. 2 shows a detail equipment of the same. Fig. 3 a lever control for the same.

Fig. 4 a detail of differential control.

Fig. 5 a modification of the same, and

Fig. 6 a sectional view of a substitute form of driver's control.

In the arrangement shown in Fig. 1 I have indicated diagrammatically a rear window as at 1 equipped with a rear curtain 2 on a roller 3. I have deliberately illustrated this roller as positioned at the bottom of the window 1 as this I believe to be the logical position, although the roller generally is positioned at the top of the window. The position of the roller is immaterial as the only difference in control between one position and the other is that of pulley arrangement.

As a controlling medium I provide a cord or wire 4 which runs over a pair of window pulleys as at 5 and a corner pulley as at 6. When the equipment is put on as an accessory these cords or pulleys are exposed but they can, of course, be built into the car and concealed beneath the upholstery where such equipment is made standard.

The control line 4 is interrupted at any convenient point, one portion being attached to and spooling upon the larger drum 7 of a differential pulley and the other portion of the line 4 being attached to the smaller drum 7' of such a pulley and so arranged to wind and unwind with any desired ratio according to the relative diameters of the two drums.

I am able in this way to reduce the hand movement of the driver to a minimum so that in a single short motion he can give a complete pull to the curtain even though the rear window be of maximum size. Such rear windows do vary in size considerably but my device is proportioned to take care of the maximum.

The position generally recognized as most desirable for the driver's control is one easily reached by the left hand when seated at the wheel. This may be on the dash as heretofore suggested or may be very conveniently positioned just above the driver's head, as for example, just above the door at the driver's left. For such a position I have devised a very simple and positive operating device. This consists of a lever 8 pivoted in a bracket 8' so as to have a horizontal front and rear

swing. The cord 4 may be adjustably attached as at 8² to accommodate variations in the height of the rear window. The horizontal swing of the lever 8 moves it in a path that is clear of the door and convenient to the driver. Only a short lever is required as the effective pull on the cord 4 is double that of the lever and with the advantage of the differential connection 7 the maximum rear window is easily served.

I preferably provide a tubular well 9 and carry the cord forward with a weight W on its end which works free in the well 9. As a modification of this arrangement I have shown in Fig. 2 a very inexpensive structure in which I have provided a ring 10 on the line 4 and a series of hooks 11 with which the ring can be engaged.

As a further modification of the driver's adjusting means I have shown in Fig. 4 a reel 12. This is preferably mounted on a base 12¹ on the outer face of which are a series of recesses 12^a. The reel is provided with a handle 13 normally urged inward by a spring 14 and the whole assembled on a single screw 15.

The differential pulley 7 is shown in Fig. 4 in its simplest form but is obviously capable of variation as indicated in Fig. 5. In this I have shown the large pulley 16 geared through 17 to a large gear 18 carrying a small pulley 19. This is a more expensive construction but is capable of giving a wider range of differential where the proportions of the car require it or where it is desired to still further limit the motion required of the driver.

I have illustrated these various forms of control as indicating the range made possible by the use of my differential. Other variations and modifications will be obvious to those skilled in the art.

What I therefore claim and desire to secure by Letters Patent is:

1. In combination with the back window curtain of an automobile, a front seat control therefor comprising an interrupted pull cord system, a differential winding and unwinding drum pair interposed between the parts of the pull cord to give a maximum curtain movement with a minimum movement of the pull cord at the front seat, a takeup weight on the end of the pull cord, a tubular well for slidably receiving said weight, and means adjacent the driver's seat for adjustably controlling the cord.

2. In combination with the back window curtain of an automobile, a front seat control therefor comprising an interrupted pull cord system, a differential winding and unwinding drum pair interposed between the parts of the pull cord to give a maximum curtain movement with a minimum movement of the pull cord at the front seat, and a lever pivoted adjacent the driver's seat for forward and

rearward movement and having the cord attached adjacent its free end, a takeup weight on the end of the pull cord, a tubular well for slidably receiving said weight, and means adjacent the driver's seat for adjustably controlling the cord.

3. In combination with a back window curtain of an automobile, a front seat control therefor, comprising an interrupted pull cord system, means interposed between the parts of said pull cord to give maximum curtain movement with a minimum movement of the pull cord, means adjacent the driver's seat for operating said pull cord and consisting of a lever having the cord attached adjacent its free end, said lever having a horizontal front and rear swing in a path free from interference with other parts of the automobile, and take-up means for said cord when said curtain is in raised position.

4. In combination with a back window curtain of an automobile, a front seat control therefor comprising an interrupted pull cord system, means interposed between said pull cord parts to give a maximum curtain movement with a minimum movement of the pull cord at the front seat, means for operating said cord adjacent the driver's seat and take-up means for said cord.

5. In combination with a back window curtain of an automobile, a front seat control therefor comprising an interrupted pull cord system, means associated with said system to give a maximum curtain movement with a minimum movement of the pull cord at the front seat, and means for operating said cord adjacent the driver's seat.

In testimony whereof I affix my signature.

JOHN FRANCIS CURRIVAN.
